UNITED STATES PATENT OFFICE.

HERBERT CROSSLEY AND THEODORE BIRNBAUM, OF LONDON, ENGLAND,
ASSIGNORS TO THE B. BIRNBAUM & SON, LIMITED, OF SAME PLACE.

MECHANICAL TOY.

SPECIFICATION forming part of Letters Patent No. 536,512, dated March 26, 1895.

Application filed October 15, 1894. Serial No. 526,001. (No model.)

To all whom it may concern:

Be it known that we, HERBERT CROSSLEY, gentleman, residing at 78 Portland Place, Marylebone, in the county of London, and THEODORE BIRNBAUM, india-rubber manufacturer, residing at Wick Lane Rubber Works, Bow, London, in the county of Middlesex, England, subjects of the Queen of Great Britain, have invented new and useful Improvements in Mechanical Toys, of which the following is a specification.

This invention has reference to certain constructions of parts of mechanical toys especially adapted for toys made wholly or mainly of india rubber so as to enhance the pleasure and amusement afforded by their exhibition by enlarging the range of imitativeness and life like appearance in their performances without so increasing their cost as to preclude their general sale.

Our improved toys can be varied considerably as to the outward form—whether they are made to resemble an animal, a bird, a reptile or any other animate or inanimate moving object—and although in explaining the construction and operation of our improved toys we have selected as an illustration a frog, we do not by any means intend thereby to limit the range of application of the invention.

The material which we have found most conveniently to lend itself to our purpose is india rubber but other suitable elastic material can be employed alone or in combination therewith.

Where it is merely desired to protract and retract the limbs or parts of the animal or toy the body and parts are formed either in one main hollow construction, or in separately inflatable chambers, and by pressure of fluid passed thereto as hereinafter described the normally flexed, cramped, folded or retracted positions of the limbs, parts or like connections, are altered to more or less protracted, extended or unfolded positions. The rate or rapidity of such expansion can also be readily adjusted, controlled and adapted to imitate the habits of the object portrayed.

In the body or parts of the toy may be spaces or chambers which in the case of a toy designed to be caused to dive are normally accessible to the liquid in which the toy is to

sink, while within the toy is an elastic chamber—say an inflatable india rubber bag, or diaphragm connected by tube and passage to the pump or inflating means, so that on pressure being applied a lighter fluid may be caused to distend this bag or diaphragm—expel the heavier liquid from the toy—cause its rise in or flotation upon the liquid, while movements to the limbs or parts of the natant toy may be given by means of the pump or fluid pressure, the access of pressure distending the limbs or parts, by the enlargement or distending of the joints and the withdrawal of the pressure allowing them to retract, the manipulation of the pressure affording means of imitating the characteristic movements. The pump, or distender being capable of concealment in the hand, or about the person, or under the foot of the operator and the pipes of communication being capable of being made very small and inconspicuous, an element of reality is given to the movements of the elastic distensible toy not before attainable by such simple means.

So far as we are aware pneumatic inflation in toys has only been utilized to distend an elastic body as in the case of a balloon, or equivalent bladder like body, or by causing the distention of a bellows or similar mechanism to give motion by concealed means to levers or arms acting in conjunction with springs to cause relative movements to the body and limbs of mechanical toys, but we make no claim to any such constructions as on the contrary we have found that levers and springs are liable to get out of order and detract from the naturalness of the construction imitated.

Weighting of some of the parts of the toys may be adopted but separately considered this forms no part of our invention.

The separate chambers may be separately inflated by separate passages to which pressure from the pump, or force, is conveyed by tubing or one chamber may be in fluid connection with the tube conveying the fluid pressure and another chamber say an inflatable bag for the diving regulation may only receive its access of air or fluid when a certain amount of pressure is reached sufficient to overcome the resistance offered by the valve controlling the passage way between these

chambers, and stops applied to the fluid pressure tubes may afford means of selecting those to be operated.

In the annexed drawings Figure 1, is a plan view, partly in section, of a toy frog embodying our invention. Fig. 2 represents the body portion of the toy partly in section and with the interior bladder or distention chamber partly broken away and shown in its inflated condition. Fig. 3 shows one of the hind legs separately, looking toward the joints on the outside. Figs. 4 and 5 show sections taken relatively at right angles to each other to show the method of forming the joints by building up superposed thicknesses of rubber sheet and cutting or removing portions of the inner tube at places where in the molding the joints or expandible vessels are to be formed. Fig. 6 is a partly sectional plan illustrating a modification in the arrangement of chambers in the body portion of the toy. Figs. 7 and 8 are sectional views of the modified form of toy body, at right angles to Fig. 6. Fig. 9 is a cross-section of leg at 1-1 of Fig. 6. Fig. 10 is a plan of the lower end of leg, and Fig. 11 a cross-section of the same at 2-2, Fig. 10. Fig. 12 is a sectional view of a toy frog showing modifications in the means for effecting inflation, the inflating device being provided with a plurality of tubes. Fig. 13 is a sectional view of a bi-tubular inflating device. Fig. 14 is a section of one half of a toy frog with limbs in normally flexed position. Fig. 15 is an exterior view of the other half of the toy frog with limbs extended.

Referring, first, to Fig. 1, the letter *a* designates the skin or casing of the toy frog, which may be composed of india rubber or other suitable elastic material.

40 *b* is the body of the frog containing the air vessel *c*. This body chamber *b* has passages *b'* for inlet and exit of water when the frog is in that medium.

45 *d* is an air passage which is continued down the hind legs; and by the tube *c'* is in communication with the chamber *c*, such communication being controlled by a valve at *c'*. *e* is a tube leading from this passage *d* to a suitable air forcing means (as an air injector 50 rubber ball see *f* in Fig. 6).

55 In the modified construction shown in Fig. 6, the body *b* is divided into two chambers by the inclined elastic partition *b²* shown more clearly by the two cross sections Figs. 7 and 8, *d* being an air receptacle capable of dilation and *g* being water space contractible by the dilation of the partition *b²*.

60 In the tube *e* we prefer to insert a short length of rigid and heavier tubing, so as to aid in the sinking of the said tube below and free of the frog body and generally to facilitate correct operation.

65 Taking as an example the foregoing illustrations of a practical embodiment of the invention in a frog which is to be made at will to crawl, spring, swim, or dive, the operator holds the distending device or inflater or de-

flator *f* and by the tube *e* effects inflation and deflation of an invisible bladder or vessel *c* within the body *b* so that specific gravity 70 of the toy may be made less or greater than that of the water, (or being so desired the body may distend also) and the toy be caused to swim or sink. Gradual deflation may be provided for by a pin hole in the vessel *c*. At the same 75 time the inflating fluid may pass to vessels which when inflated or deflated control the connected limbs, or parts, suitable valvular stops operated by the performer enabling selection of the parts operated to be effected. 80

By forming the limbs or parts *h* with spaces or chambers *h'* suitably located therein with a normal tendency to keep a contracted form, as when a frog has his limbs tucked up ready for a jump (as shown by the left hind leg in 85 Figs. 1 and 6) and providing fluid passages connected either through the body bladder or directly to the distender *f* held by the performer, a slow crawling progression or a sudden jump or swimming or diving action can 90 with a little practice be readily obtained, by the adjustment of the force of distention.

According to a modification illustrated in Figs. 12 and 13 the distender *f* may be provided with duplicate tubes or a set of tubes 95 connecting it to the toy, the selected tubes being put into or kept out of use by valves acted on by the performer's fingers. In this instance the hind legs are operated in the manner already described while the front 100 legs *i*, which are formed with collapsible recesses *i'*, are in communication with the distender *f* by a separate tube *e'*, here shown as connected by a branch tube *e²* for supply of air. 105

Stop pieces or valves *f'* *f'* are provided adjacent to the junction of the tubes *e* *e'* with the distender *f* by which the performer may close one or other tube thereby regulating the supply of air to the selected limb or 110 limbs. By such means varied movements may be given to a selected limb or limbs and they may be operated as desired.

In using the examples already described as a diving toy, the body *b* by suitable inlets *b'* 115 becomes more or less filled with water which the inflation of the vessel *d* or bladder *c* within more or less displaces allowing the toy to rise or fall therein while the impulses to the limbs produce motion; or in some cases 120 the inlet and exit *b'* see Figs. 7 and 8 may be at about the point 3 so that emission of water thereabout may aid progression in the water in which the toy is swimming.

In Figs. 14 and 15 is shown a modified construction in which the inflation and deflation of the whole body and limbs of the toy is effected from one tube connected at *e'*. 125

The body or main bladder may be fed by a separate tube, or by means of a suitably constructed and adjusted valve, the surplus air used for working the limbs may be made to pass into the bladder at will according to the amount of pressure to be applied. 130

The toes or parts of the limbs may be made so as to have a tendency to grip the ground, or hold the water in one direction of motion while they slide over or through the supporting medium in the other direction. See Figs. 5, 10 and 11.

What we claim as our invention is—

1. A mechanical toy comprising a hollow inflated body having inflatable limbs molded in normally flexed positions and communicating with the body portion, and an inflating device connected with the body portion of the toy by a tube or tubes, whereby the body and limbs may be caused to move in a natural manner, substantially as described.

2. A mechanical toy having a body portion inclosing an inflatable chamber and provided with hollow normally flexed limbs in communication with said chamber and adapted to be inflated and thereby caused to assume extended positions, substantially as described.

3. A mechanical toy composed of a body portion having hollow normally flexed limbs adapted to be extended by inflation and provided with hollow joints that constitute expandable vessels or chambers in said limbs, substantially as described.

In testimony whereof we, the said HERBERT CROSSLEY and THEODORE BIRNBAUM, have hereunto set our hands this 27th day of September, 1894.
